WASHING APPARATUS FOR HOLLOW WARE

Christopher Edmund Linnit and Bernard
William Downs, Hastings, England

Application April 22, 1948, Serial No. 22,608

5 Claims. (Cl. 15—211)

1

This invention relates to washing apparatus for hollow ware, such as glasses, tankards, mugs, milk bottles, jars and the like, which apparatus is of the kind comprising an upright core extending up through apertures in layers of flexible material secured at their edges to a frame, which flexible layers are provided with flexible elements extending inwardly towards the core while the core has a number of flexible elements extending outwardly from it. In use, the assemblage is disposed in a vessel containing the washing liquid, and the hollow ware is pushed up and down over the core between the flexible elements on the core which wipe the inside surface of the article and the inwardly directed flexible elements which wipe the outside of the articles. The object of the invention is to provide an improved means for mounting the aforesaid layers of flexible material on the frame.

According to this invention, a washing apparatus of the kind referred to is characterised in that the peripheral edge of each layer of flexible material is gripped between two flanges of a ring which is U-shaped in cross-section with the bend of the U directed outwardly, each of which rings is mounted on said frame. For example, each ring may be shaped similarly to a hollow truncated cone of small axial length with the bend between said limbs disposed at the greater diameter, each of which rings is mounted on said frame so that its bend is lowermost. The aforesaid frame may comprise a number of upright arms disposed around and spaced away from said core and having niches formed on their inner side in which said rings rest.

The aforesaid arms may be formed from metal strips which are secured at their lower ends to a base which also supports said core and which arms are sufficiently resilient to enable them to be deflected outwardly for the insertion of said rings and means are provided for tying the upper ends of the arms together after the insertion of the rings.

The aforesaid tying means may comprise one of said rings which is supported by the outside of the upper extremities of said arms and secured thereto by clamping screws or the like.

The lower ends of said arms may be bent inwardly and secured to a metal plate to which said core is also attached, and a sucker has its upper

2

wall clamped between said plate and an under plate.

The following is a description of one washing apparatus according to this invention, reference being made to the accompanying drawings, in which:

Figure 1 is a side elevation of the apparatus showing certain parts in section, and

Figure 2 is a plan of the arrangement shown in Figure 1.

As will be seen from Figure 1, the base of the apparatus comprises a sucker 10, an apertured upper wall 11 which is recessed on its underside to receive a washer 12 and is likewise recessed on its upper face to receive a plate 13. The upper wall is clamped between the plate and washer by means of clamping screws 14. A rubber washer 15 rests on the plate 13 and has mounted over it the lower end of a core 16 which is encountered by a ferrule 19. A rubber washer 9 within the ferrule abuts against the washer 15. The core is held in position on the washer 15 by a screw 17 which extends up through the plate 13 and the washers 15 and 9 into the extremity of the core 16. Secured to the plate 13, for example by rivets 20 or by welding, are the lower ends 20 of three upwardly-extending arms 21. The inner face of each arm is provided with niches 22 the lower two of which serve to support the lower two of 30 rings 23. Each ring is U-shaped in cross-section with the bend 24 of the U resting in said niches. The two limbs 25 of the U are arranged to grip between them a layer of rubber 26. The rings are initially formed so that the width between the limbs is sufficiently great to enable the peripheries of the layers to be inserted, whereafter the limbs are spun inwardly; preferably the rings are formed from aluminium alloy. It will be noted that the rings are so shaped as to be similar to truncated cones of small axial width. The bend between the limbs is arranged lowermost. The uppermost ring 23 is arranged to rest on the outside of the extremities of the arms 21 and is secured to each arm by a set-screw 27 and nut 28.

45 A washer of comparatively thick rubber 29 is arranged to overlie the lower extremities 20 of the arms and to form a buffer. The core is provided with a number of circumferential grooves disposed between the rings 23 and spun into each groove is the inner periphery of an annular mem-

ber formed of rubber sheet so as to provide a number of outwardly-directed flexible elements 30. The top of the core has secured to it a number of upwardly-extending flexible elements 31. As will be seen from Figure 2, the layers 26 are so shaped as to provide a number of inwardly-directed flexible elements 32.

We claim:

1. A washing apparatus comprising an upright core, a number of flexible elements extending out from said core, a frame encircling and carrying said core, a number of apertured spaced layers of flexible material encircling the core and provided with inwardly directed flexible elements a number of rings each of U-shaped cross-section and shaped similarly to a hollow truncated cone of small axial length with the bend of the U arranged outermost, each of which rings encircles the periphery of a layer with the flanges of the U gripping opposite sides of the layer, said frame being provided with seatings for the aforesaid rings and means for retaining said rings on their seating.

2. A washing apparatus comprising an upright core, a number of flexible elements extending out from said core, a frame comprising a number of upright arms disposed around and spaced away from said core and secured at their lower end to said core, a number of apertured spaced layers of flexible material encircling the core and provided with inwardly directed flexible elements, a ring of U-shaped cross-section encircling the periphery of each layer with the flanges of the U gripping the opposite sides of the layer, said upright arms of the frame being provided with niches for supporting said rings, and means for retaining the rings in said niches.

3. A washing apparatus comprising an upright core, a number of flexible elements extending out from said core, a frame comprising a number of upright flexible metal arms, a base secured to the lower ends of the arms and supporting said core, a number of apertured spaced layers of flexible material encircling the core and provided with inwardly directed flexible elements, a ring of U-shaped cross-section encircling the periphery of each layer with the flanges of the U gripping opposite sides of the layer, said upright arms being formed with niches into which the rings are adapted to be sprung and means for tying

the upper ends of the arms together after the insertion of the rings.

4. A washing apparatus comprising an upright core, a number of flexible elements extending out from said core, a frame comprising a number of upright flexible metal arms, a base secured to the lower ends of the arms and supporting said core, a number of apertured spaced layers of flexible material encircling the core and provided with inwardly directed flexible elements, a ring of U-shaped cross-section encircling the periphery of each layer with the flanges of the U gripping opposite sides of the layer, said upright arms being formed with niches into which the rings are adapted to be sprung, and set screws clamping the outer ring to the extremities of said arms so as to tie them together and hold the other rings in position.

5. A washing apparatus comprising an upright core, a number of flexible elements extending out from said core, a frame comprising a number of upright flexible metal arms, a metal plate secured to the lower ends of the arms and supporting said core on one side thereof, a number of apertured spaced layers of flexible material encircling the core and provided with inwardly directed flexible elements, a ring of U-shaped cross-section encircling the periphery of each layer with the flanges of the U gripping opposite sides of the layer, said upright arms being formed with niches into which the rings are adapted to be sprung, and means for tying the upper ends of the arms together after the insertion of the rings, and a single sucker arranged on the other side of the plate and a clamping means beneath said sucker and secured to said plate.
